Primary Examiner—Wallace R. Burke*Assistant Examiner*—M. H. Tung*Attorney, Agent, or Firm*—Richard P. Crowley[57] **CLAIM**

The ornamental design for a combined antiglare monitor filter and holder, as shown and described.

DESCRIPTION

FIG. 1 is a perspective view of a combined antiglare monitor filter and holder, the broken line drawing of a monitor is for illustrative purposes only and forms no part of the claimed design, on a reduced scale;

FIG. 2 is a top perspective view thereof, the filter holder shown separately for clarity of illustration;

FIG. 3 is a top plan view thereof;

FIG. 4 is a front elevational view thereof;

FIG. 5 is a side elevational view thereof, the opposite side being a mirror image;

FIG. 6 is a rear elevational view thereof;

FIG. 7 is a bottom plan view thereof;

FIG. 8 is a side elevational view thereof, the opposite side view being a mirror image; and,

FIG. 9 is a top plan view thereof.
